[57] CLAIM

The ornamental design for a splash guard for a fuel dispensing nozzle, as shown and described.

DESCRIPTION

FIG. 1 is a left side elevational view of a splash guard for a fuel dispensing nozzle showing my new design;

FIG. 2 is a rear elevational view thereof;

FIG. 3 is a right side elevational view thereof;

FIG. 4 is a front elevational view thereof; and

FIG. 5 is a cross sectional view taken on line 5—5 of FIG. 4.

The fragmentary broken line representation of a fuel dispensing nozzle in FIG. 1 is for purposes of illustration only.

FIG. 2.

FIG. 3.

FIG. 4.

FIG. 5.
